CONTROL VALVE DEVICE

Cecil S. Kelley, Forest Hills, Pa., assignor to The Westinghouse Air Brake Company, Wilmerding, Pa., a corporation of Pennsylvania

Original application October 30, 1942, Serial No. 463,915. Divided and this application February 28, 1945, Serial No. 580,258

5 Claims. (Cl. 303—54)

This invention relates to control valve devices and more particularly to the manually operative self-lapping type for governing flow of fluid under pressure; the present application being a division of my copending application Serial No. 463,915, filed October 30, 1942.

The principal object of the present invention is the provision of a control valve device of the above general type embodying novel means for defining a maximum pressure position of the manual operating lever and for automatically moving said lever out of said position upon relief of manual force on the lever, and also embodying means adapted to render the control valve device ineffective to limit pressure of delivered fluid when said pressure exceeds a chosen degree.

Other objects and advantages will be apparent from the following more detailed description of the invention.

In the accompanying drawing, the single figure is a sectional view of a control valve device embodying the invention.

Description

As shown in the drawing, the improved control device comprises a bracket 1 upon the upper face of which is secured a base member 3 by cap screws 4. A casing section 5 is secured by cap screws (not shown) to the lower face of the base member 3 within the bracket 1.

The base member 3 has two vertically extending parallel arranged end walls only one of which is shown in the drawing and designated by the numeral 8, and between these end walls the base member is provided with a raised portion 9. The raised portion 9 has a chamber 11 adapted to be connected to a device (not shown) to be controlled by variations in pressure of fluid, and separated by a wall 12 from a chamber 13 provided above a flexible diaphragm 14. The two chambers 11 and 13 are in permanent communication with each other through a stabilizing choke 15.

The diaphragm 14 is clamped around its edge between the lower face of the base member 3 and the adjacent end of the casing section 5. An oppositely arranged and axially aligned flexible diaphragm 16 is clamped around its edge between the opposite end of casing section 5 and a cover 17. A chamber 18 is formed between the diaphragm 16 and cover 17 and is in constant communication with the atmosphere through an opening provided in an insect excluder 19. The adjacent faces of the two diaphragms 14 and 16 are open to chambers 20 and 21, respectively,

which are in permanent communication with each other through a passage 22 provided in an annular rib 23 projecting inwardly from the casing section 5 above the diaphragm 16. In use, chamber 20 is constantly supplied with fluid under pressure from any suitable source by way of a supply pipe 27 connected to the bracket 1 and opening to a passage 28 in the base member 3 which passage in turn opens to a passage 29 in the casing section 5, the passage 29 leading to chamber 20.

The rib 23 supports in chamber 20 one end of a control spring 38 the opposite end of which bears against an annular spring seat 39. The seat 39 is mounted on a stem 27 and urged by spring 38 against a shoulder 48 on said stem. The spring 38 is fully expanded with the parts of the device in the position shown and is operative to oppose downward movement of the stem 27 and thereby of diaphragms 14 and 16 from this position, as will be hereinafter described.

The central portion of diaphragm 14 is clamped between two followers 24 and 25, the follower 25 engaging an annular collar 26 provided on stem 27, which stem extends through the chamber 20 and said followers and diaphragm into chamber 13. A nut 28 disposed in chamber 13 has screw-threaded engagement with the wall of a bore 29 provided in the end of stem 27 and is tightened against the follower 24.

The rib 23 has a bore lined with a wear bushing 30 arranged in axial alignment with the two diaphragms 14 and 16, and the stem 27 extends through this bushing and centrally through the diaphragm 16 into chamber 18. Above the rib 23 the stem 27 is reduced in section to provide a shoulder 32, and a wear sleeve 31 is mounted on this reduced portion of the stem with one end in engagement with said shoulder. The sleeve 31 extends through bushing 30 in sliding contact therewith and its opposite end contacts a follower 33 which is disposed in chamber 21 in contact with the upper side of the diaphragm 16. The stem 27 extends through follower 33 and a follower 34 mounted against the opposite face of the diaphragm 16, and a nut 35 provided on the end of stem 27 in chamber 18 is tightened against the follower 34 clamping same centrally to one side of the diaphragm 16 and thereby securing the follower 33 against the opposite side of the diaphragm.

An adjusting screw 36 having a screw-threaded connection with cover 17 extends through said cover into chamber 18 in alignment with nut 35 for engagement thereby. A lock nut 37 is pro-

vided on screw 36 for engagement with the exterior of the cover 17 to lock said screw in an adjusted position.

The nut 28 above diaphragm 14 has an upwardly extending sleeve-like projection 40 the end of which is mounted to slide in one end of a sleeve 41. This end of sleeve 41 is secured in a bore through wall 12 and the sleeve extends through chamber 11 and the opposite wall thereof in the raised portion 9 of the base member 1 to a point above said raised portion.

The bore 29 in the diaphragm connecting stem 27 is in permanent communication through a smaller bore 42 and one or more radial ports 43 with chamber 20 and contains a fluid pressure supply valve 44 having a fluted stem 45 extending through an axial bore provided in nut 28 into the projection 40 thereof wherein it contacts a fluid pressure release valve 46. The nut 28 is provided with a seat for engagement by the valve 44 and a spring 49 extending through bore 29 and 42 acts on said valve for urging same into contact with said seat.

A plunger 50 is slidably mounted in sleeve 41 above the release valve 46 and is provided with an annular groove 51 in which there is disposed a sealing ring 52 contacting the bottom of said groove and the wall of said sleeve for preventing leakage of fluid under pressure from a chamber 53 below the plunger to an annular chamber 54 above the plunger. The chamber 53 is in permanent communication with the interior of the sleeve projection 40 of nut 28 and through one or more radial ports 55 in sleeve 41 with chamber 11. The chamber 54 is constantly open to the atmosphere through one or more radial ports 56 provided in sleeve 41 above the plunger 50.

The plunger 50 has a portion 57 of reduced section depending therefrom into chamber 53 and provided with an axial bore opening through a valve seat on its lower end which is provided for engagement by the release valve 46. The release valve 46 has a fluted stem 58 extending through this bore into a bore 59 of larger diameter in which there is slidably mounted a spring seat 60 having one or more openings 61 adjacent its peripheral edge connecting the spaces at opposite sides of said seat. The plunger 50 also has an upwardly projecting portion 62 of reduced section extending through chamber 54 and in sliding engagement with an inturned collar 63 provided at the upper end of sleeve 41. The bore 59 extends to a point above collar 63 where it joins a screw-threaded bore 64. Just below the end of the screw-threaded bore 64, the portion 62 of plunger 50 has two oppositely arranged radial bores 65 in which are disposed pins 66 extending from opposite ends of a cylindrical spring seat 67 which is of slightly smaller diameter than bores 65 so that said seat may be inserted into bore 59 through either of the bores 65. A coil spring 68 is disposed in bore 59 under pressure and acts at one end on the spring seat 67 and at the opposite end on the spring seat 60, this spring biasing the release valve 46 to its open position shown and moving the spring seat 67 upwardly until the pins 66 engage the uppermost portions of the bores 65 in which position the spring seat 67 is held against longitudinal movement and thus secured within the bore 59.

An operating screw 70 is threaded into bore 64 and on its outer end is provided with a head 71. A lock nut 72 on screw 70 is arranged to engage the end of the extended portion 62 of plunger 50 for securing the screw 70 in an adjusted position.

A coil bias spring 73 under pressure encircles the portion of sleeve 41 extending above the raised portion 9 of the base member 1 and is supported at one end on said member while its opposite end bears against a ring-shaped seat 74 secured on the portion 62 of plunger 50 by suitable interlocking means 75.

Directly above the operating screw 70 and extending at right angles to the axis thereof is an operating shaft 120 which is journaled at opposite ends in the two end walls including the end wall 8. A cam 126 is mounted on shaft 120 above the screw 70 and a key 129 secures said cam for rotation by said shaft. A manual operating lever 131 is provided for turning the shaft 120 and cam 126 to a "neutral" position in which it is shown in the drawing and out of said position in either direction. For the purpose of illustration the lever 131 may be turned from "neutral" position in an "ahead" zone or direction to "stop," "slow," "full" and "start" positions, and in an "astern" zone or direction to reversely arranged like positions, which positions are indicated by legends in the drawing.

25 A fulcrum bar 148 extends between and is carried by the end walls including the end wall 8, and an end of said arms is rockably mounted on said rod. The opposite or free end of said arm is disposed between the peripheral surface of cam 126 and the head 71 of the adjusting screw 70 in the upper end of plunger 50, said free end being provided on one side with a rounded surface 200 having sliding contact with the screw head 71. In the opposite side of the free end of arm 152 30 is a recess formed between two jaws 201 and in which is disposed a roller 202 mounted to roll on a pin 203 carried by said jaws. The roller 202 is thus aligned for contact with the peripheral surface of cam 126 and it is constantly maintained in contact therewith by the pressure of spring 73 applied through seat 74 to the extension 72 of plunger 50 and thus through the surface 200 on arm 152 to the roller 202.

In the peripheral surface of cam 126 is a recess 45 204 arranged to receive the roller 202 with the operating lever 131 in its "neutral" position. The screw 70 in the extension 62 of plunger 50 is so adjusted that with the lever 131 in "neutral" position and with the diaphragms 14 and 16 in their normal positions and with the supply valve 44 seated as shown in the drawing, the release valve seat on the depending portion 57 of the plunger 50 will be spaced from the release valve 46 a chosen distance due to the action of spring 55 68 on the stem 58 of said valve which maintains same in constant contact with the stem 45 of the supply valve 44.

At one side of the recess 204 the cam 126 is provided with a surface 205 for contacting the roller 202 while at the opposite side of the recess is an identical surface 206 for contacting said roller, these two surfaces being arranged reversely so that the surface 205 will displace the roller 204 and thereby the plunger 50 from normal position shown in the drawing in a downwardly direction upon movement of the operating lever 131 from "neutral" position into the "ahead" zone, while the surface 206 is provided to accomplish the same result upon movement of lever 131 in the opposite direction from "neutral" position into the "astern" zone.

Referring particularly to surface 205. When the control lever 131 is turned into the "ahead" zone, this surface is arranged to move the depending portion 57 of the plunger 50 into engage-

ment with the release valve 46 and to then actuate said valve to open the supply valve 44 to a certain extent by the time the operating handle attains the "stop" position. Further movement of the operating lever 131 from "stop" position to "full" position in the "ahead" zone will then provide gradually an increased displacement of the plunger 50 in a downwardly direction. Continued movement of the operating lever from "full" to "start" position in the "ahead" zone will then provide still further downward movement of the plunger 50 and preferably of a greater degree for the extent of lever movement than obtained between the "slow" and "full" positions for corresponding movement of the operating lever. The end of surface 205 opposite recess 204 joins an abrupt rise 207 formed substantially at the radius of roller 202 and which is provided for contact with said roller in the "start" position of the operating lever 131 for defining such position and preventing movement of said lever past same.

The portion of surface 205 engaged by roller 204 between the "full" and "start" positions is of such slope that the pressure of spring 73 applied through the roller 202 to said surface tends to return the lever 131 from the "start" position to the "full" position. The purpose of this tendency is to automatically return lever 131 from "start" position to "full" position upon removal of manual force from said lever and this may be obtained by the sole action of spring 73 as just described.

From the above description it will now be seen that plunger 50 will occupy its most elevated position with respect to cam 126 when the operating lever 131 is in its "neutral" position and due to action of cam surface 205 upon movement of said lever out of said position into the "ahead" zone, said plunger will be displaced downwardly from its normal position to an extent dependent upon the position of the operating lever away from "neutral" position, the maximum displacement of said plunger being attained in the "start" position.

Upon movement of lever 131 from "neutral" position into the "astern" zone the cam surface 206 and an abrupt rise 208 at the end of said surface opposite recess 204 is arranged to function identically to surface 205 and rise 207 upon movement of the operating lever 131 in the "ahead" zone as above described.

An inverted substantially U-shaped cover 210 extends over and is carried by the end walls including wall 8 and is secured at opposite ends to the base member 3 by screws 212.

Certain parts of the structure shown in the drawing have not been described since a description thereof is not essential to a clear understanding of the invention, but, if desired, reference may be made to the parent application hereinbefore referred to for a complete description thereof.

Operation

In operation, let it be assumed that the supply pipe 71 is connected to any suitable source of fluid at a pressure such as eighty-five pounds per square inch as a result of which fluid at the same pressure will be effective in chamber 20 between the two diaphragms 14 and 16. Due to the fact that the opposing areas of diaphragms 14 and 16 are the same, the pressure of fluid in chamber 20 acting on one diaphragm will equal and balance that acting on the other diaphragm. Also

let it be assumed that the operating lever 131 is in "neutral" position and that the adjusting screw 70 has been adjusted to allow, in said position, unseating of the release valve 46 with the control spring 38 fully expanded. As a result, chamber 11 and chamber 13 will be open to atmosphere past the release valve 46, spring seat 60, chamber 54 surrounding the extension 62 of plunger 52 and thence through port 56.

Now let it be assumed that the operator moves the operating lever 131 to "stop" position in the "ahead" zone. This movement actuates the cam 126 to move plunger 50 into seating engagement with the release valve 46 and to then move said valve to unseat the supply valve 44 to a slight extent. Fluid under pressure supplied to chamber 20 between the two diaphragms then flows past the supply valve 44 to chamber 11 and thence to the device (not shown) to be controlled by such pressure. At the same time as fluid is thus supplied to chamber 11 it also flows from said chamber through the stabilizing choke 15 to chamber 13 above the diaphragm 14 wherein the pressure increases substantially with the increase in chamber 11. When the pressure thus obtained in chamber 13 and acting on the upper face of diaphragm 14 becomes increased to a sufficient degree to overcome spring 38, the diaphragms 14 and 16 are deflected downwardly relative to the supply valve 44 and finally moves nut 28 into engagement with said valve for preventing further flow of fluid under pressure to chambers 11 and 13. The supply valve 44 is thus closed in a position of the diaphragms 14 and 16 and in a pressure condition of spring 38 determined by the extent of downward movement of said valve by the cam 126 and therefore by the position of lever 131, and it may be assumed that this occurs when the pressure in chambers 11 and 13 is increased to a degree such as ten pounds with the operating lever in the "stop" position.

If the lever is now moved from "stop" position to "slow" position in the "ahead" zone the supply valve 44 is displaced downwardly further and out of seating contact with nut 28 following which fluid will again flow from diaphragm chamber 20 to chamber 11 and thence to chamber 13. The consequent increase in pressure in chamber 13 will then move the diaphragm 14 downwardly to again cut-off the supply of fluid past the valve 44 when the pressure in chamber 11 is increased to a degree corresponding to the new position of the supply valve 44 as determined by the control lever 131 in the "slow" position.

If the operating lever 131 is now moved from the "slow" position to "full" position in the "ahead" zone; a corresponding further downward movement of the supply valve 44 away from the end of nut 28 will occur to allow further flow of fluid under pressure from chamber 20 to chamber 11 and thence to chamber 13 at the upper side of diaphragm 14 and as a result the diaphragm 14 will be deflected downwardly further against spring 38 and again cause seating of the nut 28 against the supply valve 44 when the pressure in chambers 11 and 13 is increased to the degree called for by the position of the operating lever. The pressure attained in chambers 11 and 13 in "slow" position of lever 131 may for instance be twenty pounds per square inch while that attained in "full" position may be of a degree such as sixty pounds. If instead of being moved to the "full" position the lever 131 is moved to a position intermediate the "slow"

and "full" positions, in the "ahead" zone, the corresponding downward movement of the supply valve 44 will result in a corresponding less degree of pressure being attained in chambers 11 and 13. Thus the pressure attained in chambers 11 and 13 may, by proper positioning of the control lever 131 between the "slow" and "full" positions in the "ahead" zone be limited to any desired intermediate degree.

If the operating lever is now moved from "full" position to "start" position the supply valve 44 will again be unseated for increasing the pressure of fluid in chambers 11 and 13 which will cause further downward movement of the diaphragms. However, upon a slight downward movement of the diaphragms in response to this increase in pressure in chamber 13 the nut 35 on the end of the diaphragm connecting stem 21 will preferably engage the adjusting screw 36 and limit such downward movement to a position in which the supply valve 44 will be maintained open in order that the pressure in chambers 11 and 13 may increase to the maximum degree effective in chamber 20 between the diaphragms, or to a pressure such as eighty-five pounds.

Upon removal of manual force on lever 131 in the "start" position, said lever will automatically be returned to "full" position by forces hereinbefore described and aided by the pressure of fluid in chamber 11 acting in the plunger 50. Since the pressure in chamber 13 will initially hold the diaphragms 14 and 16 against movement by spring 38 upon such movement of lever 131, spring 47 will hold the supply valve 46 seated and the depending portion 57 of plunger 50 will therefore be moved by spring 73 and the pressure of fluid in chamber 11 acting on said plunger away from the release valve 46 which at this time will be held against movement by spring 68. As a result, fluid under pressure will flow from chamber 11 and chamber 13 past the release valve 46 to the atmosphere. When the pressure of fluid in chamber 13 above diaphragm 14 is thus reduced sufficiently, the spring 38 will move the diaphragms 14 and 16 in an upwardly direction and through the supply valve 44 move the release valve 46 into seating engagement with the depending portion 57 of plunger 50 at the time the pressure of fluid in chambers 11 and 13 becomes reduced to the degree (sixty pounds) called for with the operating lever 131 in the "full" position.

If the operating lever 131 is now returned from "full" to "slow" position the consequent upward movement of plunger 50 by spring 73 will again unseat the release valve 46 as a result of which the pressure in chamber 11 and in chamber 13 above the diaphragm 14 will again reduce past the release valve 46 and as this reduction takes place the diaphragm spring 38 will move the diaphragms 14 and 16 upwardly to cause seating of the release valve 46 at the time the pressure of fluid in said chamber becomes reduced to the degree (twenty pounds) corresponding to the "slow" position of the operating lever. If the operating lever is returned only part way from "full" position toward "slow" position the pressure in chambers 11 and 13 will be correspondingly reduced, as will be apparent. If the lever is now returned from "slow" position to "stop" position, the plunger 50 will again be moved away from the release valve 46 by spring 73 and the pressure of fluid in chamber 11 and chamber 13 above the diaphragm 14 will then reduce and the spring 38 will act through spring 47 to seat

the release valve 46 when this pressure is reduced to the degree (ten pounds) determined by the position of the operating lever. Return of the operating lever 131 to "neutral" position will permit plunger 50 to move to a position in which the release valve 46 will remain open as shown in the drawing and above described.

Since the surfaces 206 and 208 in the cam 126 are the same as the surfaces 205 and 207 except for being reversed, it will be evident that if the handle 131 is moved into the "astern" zone, the valve structure, including plunger 50, diaphragms 14 and 16 and the supply and release valves 44 and 46 respectively, will operate in the same manner as above described to provide in chambers 11 and 13 the same pressures of fluid in the corresponding but reversely arranged positions of lever 131. Also, engagement between the cam surface 208 and roller 204 will define the "astern start" position of lever 131, and upon removal of manual force from said lever, the pressure of spring 73 and of fluid in chamber 53 on the end of plunger 50 urging the roller 200 against surface 208 will automatically return said lever to the adjacent "full" position.

Summary

From the above description it will now be seen that the valve structure including the diaphragms 14, 16, the supply valve 44, release valve 46 and plunger 50 constitutes a self-lapping valve mechanism which is operable to provide fluid in chamber 11, for controlling a device (not shown) which may be connected to said chamber, at a pressure which increases in proportion to the extent of movement of the manually operable lever out of "neutral" position in either direction to the respective "full" position. Upon movement of lever 131 past either "full" position to the respective "start" position, the stop 36 becomes effective to maintain the supply valve 44 open so that the pressure of the supply fluid in chamber 20 may become effective in chambers 11 and 13. The parts 206 and 207 in the cam 126 define and prevent movement of the lever 131 beyond either of the "start" positions, and engagement between the roller 202 and either of said parts under the pressure of spring 73 and of fluid in chamber 53 on plunger 50 is adapted to automatically move said lever out of either of said positions to the adjacent "full" position upon removal of manual pressure on said lever.

Having now described my invention, what I claim as new and desire to secure by Letters Patent, is:

1. A control device comprising in combination, a self-lapping valve device including a movable abutment subject on one side to pressure of fluid in a chamber and operable with said abutment in a normal position to open said chamber to atmosphere and upon movement of said abutment from said normal position in one direction to provide fluid in said chamber at a pressure proportional to such movement, a cam operative to control movement of said abutment, and a lever for operating said cam, said lever and cam having a normal position providing for normal positioning of said abutment and being movable from said normal position to a second position to actuate said abutment to provide fluid at a certain pressure in said chamber and being further movable to a third position for providing fluid at a greater pressure in said chamber, means arranged to resiliently secure said cam and lever in said second position against movement by pressure of fluid in

said chamber on said abutment, said cam being so designed as to render pressure of fluid in said chamber acting on said abutment in said third position effective to urge said cam and lever from said third position to said second position.

2. A control device comprising in combination, a self-lapping valve device including a plunger subject on one side to pressure of fluid in a chamber and operable with said plunger in a normal position to open said chamber to atmosphere and upon movement of said plunger from said normal position in one direction to provide fluid in said chamber at a pressure proportional to such movement from normal position, a roller engaging said plunger, a cam having a cam surface engaging said roller, a lever for turning said cam, said lever and cam having a normal position providing for movement of said plunger to normal position and being movable from said normal position to a second position for actuating said roller to move said plunger against pressure of fluid in said chamber to a second position for providing a chosen increase in pressure in said chamber, said lever and cam being movable to a third position for effecting a greater movement of said plunger against pressure of fluid in said chamber for providing a further increase in such pressure, the surface of said cam engaging said roller being so designed that in said third position said roller is engaged by said cam over substantially a quarter of its circumference to prevent movement of said cam and lever past said third position and for defining such position, means for resiliently securing said cam and lever in said second position against pressure of fluid in said chamber acting through said plunger and said roller, the surface of said cam between said second and third positions being so formed as to render pressure of fluid in said chamber acting on said plunger effective to urge said cam and lever from said third position to said second position.

3. A control device comprising in combination, a self-lapping valve device including a movable abutment subject on one side to pressure of fluid in a chamber and operable with said abutment in a normal position to open said chamber to atmosphere and upon movement of said abutment in one direction from said normal position to provide fluid in said chamber at a pressure proportional to such movement, a manually operable lever, a cam secured to turn with said lever and arranged to control the position of said abutment, said cam and lever having a neutral position providing for movement of said abutment to normal position and being operable upon movement from neutral position in one direction to effect movement of said abutment against pressure of fluid in said chamber to a degree proportional to the extent of movement of said

lever from said neutral position and being operable upon movement from neutral position in the opposite direction to effect like movement of said abutment against pressure of fluid in said chamber, a roller engaging said cam providing the operating connection therebetween and said plunger, the surface of said cam at each extreme position from neutral position of said lever cooperating with said roller to define and prevent movement of said cam and lever past such position.

4. A control valve device for regulating the pressure of fluid in a chamber comprising in combination, a plunger subject on one side to pressure of fluid in a chamber, a control spring, a movable abutment subject to the opposing pressure of said spring and of fluid in said chamber, and valve means operable by said plunger upon movement of said plunger in the direction against pressure of fluid in said chamber to supply fluid from a source to said chamber and upon movement in the opposite direction to release fluid under pressure from said chamber, said abutment being movable against said spring upon an increase in pressure in said chamber and by said spring upon a reduction in pressure in said chamber to effect operation of said valve means to either cut off the supply of fluid under pressure to said chamber or the release of fluid under pressure therefrom at a pressure in said chamber corresponding to the position of said plunger, and means operative to render said abutment immovable by fluid pressure in said chamber upon increase in such pressure above a chosen degree to thereby render said plunger operative to maintain said valve means in the condition opening said chamber to said source of fluid pressure.

5. The combination with a self-lapping fluid pressure control valve device of the type comprising a casing, two spaced coaxially aligned diaphragms in said casing, means connecting said diaphragms for movement together, said casing having intermediate said diaphragms a wall, and a spring supported on said wall and acting against the adjacent face of one of said diaphragms the opposite face of which is subject to variations in fluid pressure in a pressure chamber, of a cover member secured to said casing over the opposite face of the other diaphragm and cooperating with said other diaphragm to form a chamber open to the atmosphere, and an adjusting screw having screw-threaded engagement with said cover and arranged for engagement by the diaphragm connecting means to limit downward movement of said diaphragm by pressure of fluid in said pressure chamber.

CECIL S. KELLEY.
